(57) **CLAIM**

The ornamental design for a fitness equipment handle, as shown and described.

DESCRIPTION

FIG. 1 is a front, right, top perspective view of a fitness equipment handle, showing my new design;

FIG. 2 is a rear, left, bottom perspective view thereof;

FIG. 3 is a front elevational view of the reduced scale thereof;

FIG. 4 is a rear elevational view of the reduced scale thereof;

FIG. 5 is a left side view thereof;

FIG. 6 is a right side view thereof;

FIG. 7 is a top plan view of the enlarged scale thereof;

FIG. 8 is a bottom plan view of the enlarged scale thereof;

FIG. 9 is an enlarged view of detail 9 in FIG. 1; and,

FIG. 10 is an enlarged view of detail 10 in FIG. 2.

The dashed broken lines in the figures illustrate portions of the fitness equipment handle that form no part of the claimed design.

The dash-dot-dash broken lines are for notating enlarged views and form no part of the claimed design.

1 Claim, 10 Drawing Sheets
